(57) **CLAIM**

The ornamental design for a vehicle taillight, as shown and described.

DESCRIPTION

FIG. 1 is a perspective view of a vehicle taillight showing my present design;

FIG. 2 is a front view thereof;

FIG. 3 is a right view thereof;

FIG. 4 is a top plan view thereof;

FIG. 5 is a bottom plan view thereof; and,

FIG. 6 is another perspective view thereof.

The broken lines in the drawings illustrate portions of the vehicle taillight which form no part of the claimed design.
